UNITED STATES PATENT OFFICE.

IVAN FOX, OF LANSDOWNE, PENNSYLVANIA.

DESIGN FOR A NOSEPIECE FOR SPECTACLES OR EYEGLASSES.

SPECIFICATION forming part of Design No. 34,752, dated July 9, 1901.

Application filed April 15, 1901. Serial No. 56,024. Term of patent 14 years.

To all whom it may concern:

Be it known that I, IVAN FOX, a citizen of the United States, residing at Lansdowne, in the county of Delaware and State of Pennsylvania, have invented a new and useful Design for Nosepieces for Spectacles or Eyeglasses, of which the following is a specification, reference being had to the accompanying drawings, forming part thereof.

Figure 1 is a view in front elevation of a nose-piece showing my new design.

Fig. 2 is a view of the same in edge elevation.

As shown in the drawings, the leading or material feature of my design consists of a U-shaped loop *a*, one of the upwardly-projecting legs *b* of which is at its upper end formed with extension *c* of approximately oval general outline, set out at one edge of said leg, and of approximately twice the breadth of

said leg, said extension constituting a prolongation, so to speak, of the leg of said U-shaped loop.

Said extension embodies a central elongated aperture of breadth about equal to that of 25 the leg *b*.

The other leg *e* of the U-shaped loop is formed with a small opening, *f*, near its upper end.

I claim—

The design for a nose-piece for spectacles and eye-glasses, as herein shown and described.

In testimony that I claim the foregoing as my invention I have hereunto signed my name 35 this 24th day of January, A. D. 1901.

IVAN FOX.

In presence of—

S. SALOME BROOKE,
THOS. K. LANCASTER.
